(57) CLAIM

The ornamental design for a disposable lighter, as shown and described.

DESCRIPTION

FIG. 1 is a perspective view of my new design, wherein the phantom lines are merely to depict how decorative articles can be attached to two side grooves of my new design.

FIG. 2 is a front view thereof.

FIG. 3 is a rear view thereof.

FIG. 4 is a right end view thereof.

FIG. 5 is a left end view thereof.

FIG. 6 is a top view thereof.

FIG. 7 is a bottom view thereof; and,

FIG. 8 is an exploded perspective view of FIG. 1, wherein the decorative articles depicted by the phantom lines are exploded to illustrate how they are connected to two side grooves of my new design.

The phantom line environmental showing is for illustrative purposes only and forms no part of the claimed design.
